UNITED STATES PATENT OFFICE.

FALENTINE NEWBAUER, OF MINNEAPOLIS, MINNESOTA, ASSIGNOR OF ONE-TENTH
TO CHARLES C. TANKEL, ONE-TENTH TO MORRIS BESKIN, ONE-TENTH TO EMANUEL
NEWMARK, ONE-TENTH TO CHARLES FINN, ONE-TENTH TO SAMUEL GORDON, AND
FOUR ONE-HUNDREDTHS TO NATHAN RIVKIN, ALL OF MINNEAPOLIS, MINNESOTA.

VERTICAL-RISING AEROPLANE AND AEROFOIL.

Application filed August 25, 1921. Serial No. 495,358.

To all whom it may concern:

Be it known that I, FALENTINE New-
BAUER, a citizen of the United States, re-
siding at Minneapolis, in the county of Hen-
nepin and State of Minnesota, have invented
5 certain new and useful Improvements in
Vertical-Rising Aeroplanes and Aerofoils;
and I do hereby declare the following to be
a full, clear, and exact description of the
10 invention, such as will enable others skilled
in the art to which it appertains to make
and use the same.

This invention relates to flying machines
or aircrafts and generally to such a machine
15 adapted to rise vertically from the ground
in starting a flight, the machine also being
provided with wings by which it is sustained
for longitudinal flight.

It is an object of this invention to pro-
20 vide a flying machine with air foils of large
extent which extend substantially over the
entire wing surface, which foils form the
lifting means for the machine.

It is another object of this invention to
25 provide a wing in connection with said foils
which wing is formed of a plurality or se-
ries of pivoted sections which sections are
rotatable and arranged to be operated in
unison.

30 It is a further object of this invention to
provide such a machine with a horizontal
tail rudder composed, likewise, of a plural-
ity or series of pivoted sections, which sec-
tions are adapted to be controlled in unison
35 simultaneously with the sections of the
other wings.

It is another object of the invention to
have the sections of the wings formed with
40 camber or curved lower surface and to so
arrange these sections with their pivots on a
curve so that all of the sections in a series
co-operate to form a cambered wing.

It is still another object of the invention
45 to provide a wing which is not only formed
with a longitudinal camber, but is also bent
downwardly at its outer ends to have a
lower concave or cambered surface.

It is still a further object of the invention
50 to so construct the said air foils that they
have both a transverse and radial camber on
their undersurfaces which transverse camber
is of greater curvature at the forward por-
tion and which longitudinal or radial curva-

ture is of greater curvature near the center
of the foil.

It is also an object of the invention to
construct this foil of spaced truss members
connected by longitudinal girders and a sur-
rounding frame, the whole being covered
with a light metal material.

These and other objects and advantages
of the invention will be fully set forth in the
following description made in connection
with the accompanying drawings in which
like reference characters refer to the same
65 parts throughout the different views, and in
which

Fig. 1 is a view in side elevation of the
machine;

Fig. 2 is a view showing one of the trusses
70 of the air foil taken on the line 2—2 of Fig.
1;

Fig. 2^a is a section on the line x—x of
Fig. 2;

Figs. 3, 4 and 5 are similar views of trusses
75 used on the air foil at points indicated by
lines 3—3, 4—4 and 5—5, respectively;

Fig. 6 is a plan view of the machine, a por-
tion of one side being omitted;

Fig. 7 is a plan view on an enlarged scale
80 of the air foil, a portion of one side being
omitted;

Fig. 8 is a view in vertical section on the
line 8—8 of Fig. 7;

Fig. 9 is a view in side elevation of the
85 foil as seen from the bottom of Fig. 1;

Figs. 10 and 11 are, respectively, a view in
side and end elevation of a portion of the
foil structure;

Fig. 12 is a view in front elevation of the
90 machine, a portion of one side being omit-
ted;

Fig. 13 is a sectional view on an enlarged
scale taken on the line 13—13 of Fig. 6;

Fig. 14 is an end view of Fig. 12, as seen
95 from the right hand side; and

Fig. 15 is a perspective view of the bearing
brackets.

Referring to the drawings, the machine
comprises the customary fuselage structure
100 1 of customary design which is equipped with
two seats 1^a and 1^b with the usual control sticks
1^c. This fuselage carries the usual vertical
tail rudders 2 and vanes 3 and is supported
in the usual manner upon trucks 4 and run-
105 ner 5 with a running gear of the usual or

any standard construction, the parts of which it is unnecessary to detail.

The machine is also provided with the customary motor 5 preferably of the Liberty 5 type having the radiator 5^a. In place of propellers, the machine is equipped with two devices of an entirely distinct nature which will be referred to as air foils, and which are shown as 6. These foils are of considerable extent in plan, as shown in Figs. 6 and 7 and are mounted in the wing structure for rotation above the same. These foils rotate about fixed axes disposed substantially at the center of each half portion of the wing. In plan, these foils, as shown in Figs. 6 and 7, are in the shape of an oblique parallelogram, the longest radial side being in the direction of rotation or at the forward edge. These foils are constructed of a series of transverse girders or frames 6^a made of aluminum or other light metal, and as shown in Figs. 2, 3 and 5, these girders are provided with a plurality of openings to render the same as light as possible.

As shown in Fig. 8, each of these girders comprises four channel members, the girders being separated on an approximately central longitudinal line and the various angle members being riveted together at their central portions. The members 6^a are provided at their ends with brackets 7 having flanges which are riveted to the sides of the girders and also comprising semi-circular hubs. Through these hubs and the grooves in the ends of the girders, a pipe or outside frame member 8 is disposed, the same being brazed or welded to the semicircular hubs of bearings 7. The frame members 6^a are also connected by intermediate girders 6^b and 6^c, there being an adjacent pair of the girders 6^b disposed, one above the other, and also a pair of the members 6^c disposed, one above the other, as shown in Fig. 9. These members 6^b and 6^c are secured to the members 6^a by brackets 9 provided with semicircular hubs and semicircular flanges, the flanges being riveted to the members 6^a and the hubs being riveted brazed or welded to the members 6^b and 6^c. The members 6^b and 6^c are formed as hollow cylinders or pipes and the respective pairs of these members are joined by bracing members 6^d and 6^e also in the form of pipes which are brazed or welded thereto. The members 6^b and 6^c curve inwardly at the center of the foil where they are brazed or welded to brackets 10, which brackets are made in halves and riveted together and provided with flanges extending about the shell of the hub 11 to which they are also riveted. The pipes 6^c and 6^b are also equipped a short distance from their hub with split brackets 12 which are provided with hubs fitting thereabout to which the said members are brazed, the brackets 65 being provided with flanges by which they

are riveted together. These brackets are provided with hubs to accommodate a second pair of girders or pipes 13 which extend straight across the foil and through the members 6^a at some distance from the hub. It will also be noted that the girders 6^d immediately adjacent the hub are of short length and secured to the hub by angle brackets 6^e. The hub member 11 comprises a cylindrical shell to which are bolted top and bottom plates 11^a and 11^b by bolts extending through the radial shell and having the heads and nuts thereon at the outside of said end plates. The plates 11^a and 11^b are provided with extending hub portions adapted to receive a sleeve which will be rigidly secured thereto and supported in suitable antifriction bearings in a hub 14 mounted in the wing structure. The said sleeve projects below said hub 14 and carries one member 15 of a universal joint which is connected to another member of the universal joint which is rigidly connected to a transmission shaft 16. The shafts 16, of which there is one for each foil, extend downwardly to the sides of the fuselage and are connected by universal joints at their lower ends to the ends of the driving shaft of the motor 5. The foils are thus rotated by the motor through the shafts 16. The foils are covered by a thin layer of suitable metal, the cover being preferably corrugated. From the structure described, it will be seen that the undersurface of the foil is concave in transverse section or in a section taken parallel to the ribs 6^a and that this curvature is greater toward the front or advancing edge of the foil than at the rear portion. It will also be noted that the curvature is greater near the hub portion of the foil than at the extreme ends thereof. The outer ends of the girder or brace members 6^b and 6^c are tapered and welded or otherwise secured together and also secured in the surrounding frame member 8. It will also be noted that while the members 6^b and 6^c stop at the hub portion 11, that the curvature of the same adjacent the hub is such that if continued through the hub, the top member 6^b of the pair on one side of the foil would become the bottom member on the other side, the same being true of the members 6^c.

The machine is provided in combination with the foils, with a wing member or plane, which wing member forming the plane is composed of a plurality of series 20 of pivoted swingable sections 21. The wing comprises outside frame members 22 and cross beams 23. The ends of the frame members and the cross beams being provided with brackets 24 in which are received the journals 25 secured to the wing sections 21. The wing sections comprise spaced rib or girder members 26, as shown in Figs. 13 and 14,

which are surrounded by a frame member 27 and covered with a thin covering 28 of light metal or other suitable material. The journals 25 are secured in the two outermost 5 rib members 26 by brackets 29 having hub portions brazed to said journal members which will preferably be in the form of pipes, and flanges which are riveted to the sides of the rib member 26. The rib member 26, as shown in Fig. 13, comprises two 10 channel members, the wings of which are placed adjacent each other and riveted together in slightly spaced relation. The covering 28 is placed across the flanges of 15 the said channel members and held thereon by bolts extending between the channels having integral heads at one end and their other ends threaded and provided with nuts having flat heads and sleeves projecting between the channel members, this bolt being 20 similar to the well known bicycle spoke. The journals 25 have adjacent their ends collars 30 secured thereto and the rib members 23 shown in section in Fig. 13 have bearing 25 brackets 31 brazed or riveted thereto forming the bearings in the ends of the members 25. The sections 21 have likewise fastened thereto adjacent their ends, crank arms 32 having flanges riveted to the flanges of the 30 members 26. These crank arms project upwardly and downwardly at an angle to the general plane of the sections 21, as shown in Fig. 1 and are provided with clevis arms 33 pivoted thereto, which are in turn connected 35 by turn buckles 34. To the upper crank arm 22 on the forward section in each series of wings is connected a flexible cable 35 which runs over pulleys 36 and continues downwardly into the fuselage where it is connected 40 to one end of a double crank arm 39 connected to a lever 37 provided with the usual locking quadrant and pawl. The forward lower crank arms 22 are likewise connected to a flexible member 38 which passes over 45 pulleys at the front of the wing and passes down into the fuselage where it is connected with the opposite end of the double crank arm 39. It will thus be seen that when the lever 39 is swung the sections 21 will be oscillated on their pivots, said sections moving 50 in unison, owing to the connection between the crank arms 22 thereof. As the cables 35 lead to all of the series of sections, all of said sections of the wing will be simultaneously moved. It will be noted that the undersurface 55 of each section 21 is concave so that said sections are cambered. It will also be noted that the pivoted centers of the various sections in each series are arranged in a curve 60 so that the sections co-operate to form a wing having a cambered undersurface. When the sections are disposed in normal position they co-operate to form a substantially continuous wing.

65 Viewed from the front of the machine, the

sections 21 near the center of the wing are substantially straight but the outer two series of sections are, as clearly shown in Fig. 12, bent downwardly and at the extreme edge have a slight upward bend. The longitudinal curvature of the wing, as formed by the combined surfaces of the sections, has its undersurface cambered with a greater curvature toward the front or advancing end of the wing than toward the rear portion 75 thereof.

The machine is provided with a horizontal elevator 40 comprising two series of pivoted sections. These sections are similar in construction to the sections 21 of the wings 80 and the rudder is provided with a frame member 41 and a central beam member 42, which members carry the bearings for the journals of the sections. The structure of the journals being substantially like that 85 already described for the wing sections. The sections of the elevator are also provided with crank arms 43 projecting from their top and bottom surfaces adjacent their ends, which crank arms are connected by the 90 clevis and turn buckles, as already described for the wing sections. The forward crank arms 43 are connected by flexible cable members 44 and 45 to points on a lever 46 pivoted in the fuselage adjacent the rear seat, the 95 said cables being secured, one above and one below the pivot. This lever is provided with the usual quadrant and locking pawl and when swung, will simultaneously swing the sections of the elevator in unison. The lever 100 46 is connected by a rigid member to the lever 47 so that when one of the levers 39 or 46 is moved the other will, likewise, be moved and when the wing sections are turned, the sections of the tail rudder will 105 110 115 120 125 130 turned. It will be noted that the sections of the tail rudder are also provided with cambered lower surface which co-operate when in normal position to form a general cambered rudder surface, the pivoted sections being arranged on a curve. The movements of the wing section and horizontal tail rudder sections are controlled, as stated, by the levers 39 and 46, the levers 1° being used to control the vertical tail rudder.

In operation, when ready to start a flight, the sections of the wing and tail rudder are swung so as to be in substantially vertical planes. The motor is then started and the 120 air foils rotated at high speed. These foils lift the machine directly upward until the desired height has been obtained. By reason of the structure of the foils, in which the undersurface is curved with a greater 125 curvature toward the advancing edge, and also on account of the downward curvature at the outer ends, the air moved by the foils is crowded inwardly and rearwardly and compressed forming an intensified air shaft 130

giving a much greater lifting effect than if the surface of the foils were not so curved. This lifting effect is substantially thirty per cent more per square foot than can be obtained by a plane surface. The sections of the wing being turned vertically, offer very little resistance to the downward current of air caused by the foils.

When the desired height is obtained and 10 it is desired to progress the machine forwardly, the sections of the wing are swung at an acute angle to the horizontal, the forward portions of the sections pointing upwardly. The downward current of air 15 from the foils is thus directed against an inclined surface and the forward component of this pressure causes the machine to move forwardly. As the machine moves forwardly the pressure of air against the under- 20 surface of the sections also gives a lifting effect, the air being intensified about the plane of the wing, thus increasing the lifting or sustaining power of the air. The fact that the outer portions of the wing are turned 25 downwardly and the fact that the wing is cambered with its greater curvature towards the advancing edge also acts to direct the air rearwardly and inwardly, thus giving a compressing effect to the air and also increasing the sustaining power thereof.

When the machine is in flight it is designed to travel with its body tipped downwardly so that the axes of the foils is at an angle to the vertical. The weight of the 35 body which tends to descend by gravity is due to this tipping effect used to increase the sustaining power of the wings and the rotation of the foils contribute a forward component of force to the machine.

40 If the motor be stopped, and it may be here stated that the driving means for the foils is provided with a brake so that the foils may be held against rotation, the foils will always stop with their long dimensions 45 lengthwise of the machine so that if the machine is flying with the foils stationary the same will offer very little resistance to the forward flight. These foils, in an ordinary machine will be twenty-two feet in diameter 50 and have such a large surface that when held stationary will act as parachutes to prevent the machine from rapid descent, the curved surfaces of the foils adding greatly to this effect. The foils being driven in opposite directions, the side thrust of air is balanced and the foils always tend to produce a balanced non-tipable machine.

It will also be noted that the body of the machine is well below the line of flight, thus 60 giving proper stabilization and insuring that the air foils will not allow the machine to fall, but, as stated, will act as parachutes to insure that the same will float in a level position to the earth. The machine being 65 designed to fly forward with the front end

of the body tipped downwardly a saving of fuel in power transmission is effected.

It is known that the machines have been before proposed having a portion of the wings formed with pivoted vanes and ordinary propellers mounted over the vanes. Such vanes, however, were flat and a flat surface is impractical for a correct flying surface. It is thought the combination of an air foil together with a wing composed entirely of pivoted sections is novel and this combination is entirely different from that above mentioned.

75 From the described controller lever it is seen that the machine can be controlled from either seat in the fuselage and the wing sections and horizontal elevator sections can be, likewise, controlled.

80 While one embodiment of the invention has been illustrated, it will, of course, be understood that various changes may be made in the form, details and arrangement of the parts without departing from the scope of applicant's invention, which, generally stated, consists in the matter shown and described and set forth in the appended claims.

85 It may be stated that this machine has been actually demonstrated by the construction of a large model. This model has been operated with entire success and has been shown to have a great lifting power per unit of weight.

90 What is claimed is:

1. A flying machine having in combination, a wing portion composed of a series of pivoted cambered sections arranged in a curve co-operating to form a curved wing and an air foil mounted to rotate about a fixed axis above said wing at approximately 100 the center of said portion.

2. A flying machine having in combination a wing composed of a series of pivoted cambered sections arranged in a curve co-operating to form a curved wing and an air foil mounted to rotate about a fixed axis 110 above each half portion of said wing substantially at the center of said half portion, said air foil extending substantially over the entire length and the greater portion of the 115 width of said half portion.

3. The structure set forth in claim 1, and an elevator formed of a series of oscillatable cambered sections arranged to form a cambered surface.

120 4. The structure set forth in claim 3, and means for operating said tail rudder sections in unison with the sections of said wing.

5. A flying machine having a wing composed of a plurality of series of oscillatable 125 cambered sections, each of said series comprising a row of sections having their longitudinal edges adjacent each other, said sections co-operating to form a cambered surface, said series being arranged side by 130

side to form a continuous wing, and a pair of oppositely rotated air foils each extending over substantially the entire length of the half portion of the wing at one side of the longitudinal axis of the machine.

6. A rotating air foil for an air craft having in combination vanes having a rigid outer frame extending therearound, spaced

transverse ribs extending between said frames, intermediate longitudinally extending ribs secured to said frame and extending through and secured to said ribs and a central hub secured to said longitudinally extending ribs.

In testimony whereof I affix my signature. 15

FALENTINE NEWBAUER.
